UNITED STATES PATENT OFFICE

2,607,300

RAILWAY CAR MOVING DEVICE

Paul W. Schilling, Crookston, Minn.

Application April 11, 1949, Serial No. 88,674

2 Claims. (Cl. 105—141)

1

The invention relates to devices for moving freight cars or the like along railroad tracks and the primary object of the invention is to provide a device of the character indicated above, which is adapted to be operated on and along one of the rails of the railroad track.

Another object of the invention is to provide a device of the character indicated above equipped with rotatably mounted means engaging one of the wheels of the railroad car for driving said wheel and with a motor adapted to drive said means.

A further object of the invention is to provide a device of the character indicated above having a main frame supporting the rotatably mounted driving means and the motor and being equipped with a pair of small wheels located on the longitudinal center line of said main frame and adapted to engage the track rail and support the device on said rail.

A still further object of the invention is to provide a device of the character indicated above to the rear portion of the main frame of which a handle bar is attached to facilitate manual operation of the device.

The invention consists in the details of construction and in the combination and arrangement of the several parts of my improved device for moving freight cars or the like, whereby certain advantages are attained, as will be herein-after more fully set forth.

In order that my invention may be better understood, I will now proceed to describe the same with reference to the accompanying drawings, wherein:

Figure 1 is a view in top plan of a preferred embodiment of the device in accordance with the present invention, the motor and gear box being omitted;

Figure 2 is a view in bottom plan of the device as shown in Figure 1;

Figure 3 is a side view in elevation of the device shown in engagement with a wheel of a railroad car, the motor being indicated in broken lines;

Figure 4 is a view in section taken on line 4—4 of Figure 3;

Figure 5 is a side view in elevation of a modified form of the device in accordance with the invention; and

Figure 6 is a view in top plan of Figure 5 the motor being omitted.

The device for moving freight cars and the like along railroad tracks as embodied in Figures 1, 2, 3 and 4 comprises a main frame F which may be produced as one integral unit or may be com-

2

posed of several structural parts. It has two longitudinal side walls 10 and 11 respectively, extending parallel to each other. The forward end portions 12 and 13 respectively of said side walls extend outwardly at an angle of approximately 60 degrees to each other and upwardly at an obtuse angle to the main portion of the side walls. On the forward end of each forward side wall portion 12 and 13 a front wall 14 and 15, respectively, is formed and extends inwardly from the corresponding side wall portion at a right angle thereto. Between the inner edges of the two front walls 14 and 15 an opening is left, which is large enough to permit a portion of a railroad car wheel 16 to enter.

On the inner end of each forward side wall portion 12 and 13 an intermediate wall 17 and 18 respectively is formed and extends inwardly from and at a right angle to the adjacent forward side wall portion and parallel to the front wall 14 or 15. The intermediate walls are permanently connected with each other in the vertical longitudinal center plane of the main frame F.

Substantially Z-shaped brackets 19 and 20 respectively are secured to the inside face and adjacent to the rear end of the side walls 10 and 11 respectively so that the webs 21 and 22 respectively of said brackets extend toward each other and that the inner flanges 23 and 24 of said brackets are spaced from each other and extend downwardly parallel to each other. An axle 25 extends between the flange 23 and 24 and is rotatably supported by them. On the central portion of the axle 25 a small roller 26 is rigidly mounted and is provided with annular end flanges 27.

A reinforcing bar 28 is welded or otherwise secured at its rear end portion to the undersides of the side wall 10 and the intermediate wall 17 and extends forwardly, outwardly and upwardly therefrom. The forward end portion of said bar is welded or otherwise fastened on the underside of the front wall 14. A similar reinforcing bar 29 is secured at its rear end portion to the undersides of the side wall 11 and the intermediate wall 18 at its front end portion to the underside of the front wall 15.

A bracket 30 has an upper flange 31 with which it is welded or otherwise secured to the inside surface of the reinforcing bar 28 intermediate the ends thereof. From the upper flange 31 a web 32 extends downwardly and inwardly and on the lower end of the web 32 a downwardly extending lower flange 33 is formed. A similarly shaped second bracket 34 is secured with its upper flange 35 to the inside surface of the reinforcing bar

29 oppositely from the bracket 30. A web 36 extends downwardly and inwardly from the upper flange 35 and a lower flange 37 projects downwardly from said web 36.

A shaft 38 extends through and is rotatably supported by the two lower flanges 33 and 37, and projects laterally beyond one of the side walls, for instance the side wall 10.

A roller 39 is rigidly mounted on the shaft 38 between the lower flanges 33 and 37. The roller has a cylindrical middle portion 40 from which conical flanges 41 and 42 respectively extend. On the circumferential surfaces of the two flanges are provided longitudinally running sharp projections or teeth 43 and 44 respectively which are 15 adapted to engage the head of a track rail 45.

The small roller 26 rests rotatably on the head of the rail 45 and the relative dimensions of said small roller and of the roller 39 are such that the axis of the small wheel and the roller 20 are located at the same level above the rail.

A shaft 46 is rotatably mounted in and extends through the front wall 14 and the intermediate wall 17, and a longitudinally corrugated roller 47 is rigidly mounted on the shaft 46 between 25 the front wall 14 and the intermediate wall 17. A shaft 48 is rotatably supported by and extends through the front wall 15 and the intermediate wall 18. A longitudinally corrugated roller 49 similar to roller 47 is rigidly mounted on the shaft 30 48 between the front wall 15 and the intermediate wall 18.

On the rear end portions of the shafts 46 and 48 respectively meshing bevel gears 50 and 51 respectively are rigidly mounted and are located adjacent to the rear surfaces of the intermediate walls 17 and 18 respectively. A drive shaft 52 extends transversely through the main frame F and is rotatably supported in the side walls 10 and 11 of the frame rearwardly of and adjacent to the bevel gears 50 and 51. Two bevel gears 53 and 54 respectively are rigidly mounted on the drive shaft 52 and are arranged adjacent to the inner faces of the side walls 10 and 11 respectively. The bevel gears 53 and 54 mesh with the bevel gears 50 and 51 respectively.

On the end portion of the drive shaft 52 projecting beyond the side wall 10 a sprocket gear 55 is rigidly mounted and a sprocket gear 56 is rigidly mounted on the end portion of the shaft 38 50 projecting beyond the side wall 10. A sprocket chain 57 is trained over the two sprocket gears.

On the end portion of the drive shaft 52 projecting beyond the frame side wall 11 a comparatively large spur gear 58 is rigidly mounted and a large gear housing 59 is arranged on and secured to the main frame F above the drive shaft 52. Rearwardly of the gear housing a base plate 59 is secured to the top edges of the side walls 10 and 11 and a motor 60 is mounted on said plate. Preferably this motor is a one and one half horse power internal combustion engine driving the reduction gear transmission contained in the gear housing.

This gear transmission comprises and drives a transverse shaft 61 extending outside of the gear housing. A comparatively small spur gear 62 is rigidly mounted on the end portion of said driven shaft projecting outside of the housing and meshes with the spur gear 58.

On the under edge of each side wall 10 and 11 a bearing 63 is secured approximately half way between the rear axle 25 and the transverse shaft 38. A transverse axle 64 is journaled in said bearings and two rubber tired wheels 65 are 70

mounted on said axle. The radius of said wheels is of such length that the device is adapted to ride on the rubber tired wheels and the small roller 26 and the roller 39 are arranged above the ground, when the device is removed from the rail 45 but that the tires of the wheels 65 do not touch the ground, when the roller 26 and the roller 39 rest on said rail.

An upwardly and rearwardly extending handle bar 66 is secured to the rear portion of the main frame F facilitating manual moving of the device.

When the device is to be used to move a railroad car, it is placed on a track so that the small wheel 26 and the roller 39 rest on the head of the rail 45. The motor 60 is started driving the roller 39 by means of the spur gears 62 and 58, the transverse shaft 52, the sprocket gear 55, sprocket chain 57, sprocket gear 56 and shaft 38. The wheel 16 of the railroad car enters between the corrugated rollers and is engaged and set into rolling motion by them, since said rollers are rotated by the motor 60.

In Figures 5, 6 and 7 a modified form of the car moving device in accordance to the present invention is illustrated and the device as embodied in said figures comprises a main frame M comprising two longitudinal side walls 67 and 68 respectively and a base plate 69 secured to the top edges of the side walls and holding them in position so that they are spaced from each other and run parallel to each other. Adjacent to each end of each side wall a bracket 70 is located. Each bracket 70 has upwardly extending upper flange 71, a web 72 extending at an angle from the lower edge of the flange 71 and a lower flange 73 extending downwardly from the web parallel to the upper flange 71.

A handle bar 74 is secured to one end portion, hereinafter called the rear end portion, of one of the side walls, for instance the side wall 68, so that it extends rearwardly and upwardly from said wall. A rear axle 75 is rotatably supported by the lower flanges 73 of the rear brackets 70 and extends beyond one of the side walls, for instance the side wall 68. A front axle 76 is rotatably supported in the lower flanges 73 of the forward brackets 70 and extends beyond the same side wall as the rear axle 75. The two axles are arranged so that their axes are located at the same level below the under edge of the side walls 67 and 68 and so that they run parallel to each other.

On each of the axles 75 and 76 a roller 78 is rigidly mounted having a cylindrical middle portion 79 and outwardly flaring conical end portions or flanges 80 provided on their circumferential surfaces with longitudinal sharp projections or teeth 81 adapted to engage the head of a track rail 82 on which the device is placed. The rollers 78 are located between the oppositely arranged brackets 70 and approximately on the longitudinal center of the main frame M. On the end portion of the front axle 76 projecting beyond the side wall 68 and on the corresponding end portion of the rear axle 75 a sprocket gear 83 is rigidly mounted.

A gear housing 84 is mounted on the base plate 69 adjacent to the side wall 68 and contains a reducing gear transmission (not shown) adapted to be driven by a motor 85 indicated in broken lines in Figure 5. A transverse shaft 86 forms a part of the not shown transmission and extends outwardly of the housing 84 beyond the side wall 68.

A sprocket gear 87 is rigidly mounted on the

outside end portion of the shaft 86 and a sprocket chain 88 is trained over the sprocket gears 83 and 87 so that the rollers 78 are rotated when the motor 85 is started.

A brace bar 89 is secured to the inside surface of each side wall 67 and 68 just in front of the base plate 69 and extends upwardly and forwardly and at an acute angle to the adjacent side wall. A stub shaft 90 is secured to the brace bar 89 adjacent to the side wall 68 intermediate the ends of said brace bar and extends outwardly therefrom. Two sprocket gears 91 and 92 are rotatably mounted on the stub shaft 90 so that the outer gear 92 of the outer sprocket gear 92 is in engagement with the sprocket chain 88.

A shaft 93 extends between and is rotatably supported by the two brace bars 89 and one end portion of said shaft extends laterally beyond the brace bar adjacent to the side wall 68. A sprocket gear 94 is rigidly mounted on said end portion of the shaft 93 and a sprocket chain 95 is trained over the inner gear 92 and the sprocket gear 94.

A roller 97 is rigidly mounted on the portion of the shaft 93 located directly above the rail 82 when the device is placed on said rail. The roller 97 has a cylindrical middle portion 98 from which two conical outwardly flaring end portions or flanges 99 and 100 extend. Longitudinal sharp projections 101 are provided on the circumferential surface of the conical flange 99 and similar projections 102 are arranged on the conical flange 100.

When a railroad car (not shown) is to be moved the device is placed on the rail 82 and is pushed forwardly until the projections on the roller 98 engage the wheel 103 of the railroad car. Since the flange 104 of said wheel comes nearer to the roller 97 than the outer edge of the tread 105 the conical flange 99 of the roller engaging the wheel flange 104 is smaller than the conical flange 100 engaging the wheel tread. The motor is started and the rollers 78 are rotated in clockwise direction. The two sprocket gears 91 and 92 and the roller 97, are rotated in counter-clockwise direction so that the roller 97 exerts an upward pull on the wheel 103 rotating it in clockwise forward direction.

From the foregoing description it is thought to be obvious that a device for moving freight

cars constructed in accordance with my invention is particularly well adapted for use by reason of the convenience and facility with which it may be assembled and operated.

5 I claim:

1. In a railway car moving device, a flat elongated frame, an axle mounted transversely of the center of said frame, ground wheels mounted on the opposite ends of said axle, a second axle journalled transversely of said frame adjacent the rear end thereof, a flanged rail engaging roller centered on said second axle, a pair of spaced divergently related brackets sloping upwardly from the forward end of said frame, a shaft journalled in the lower sides of said brackets and having an end projecting laterally outward of one of the same, a V-channeled roller centered on said shaft between said brackets for driving engagement with the rail engaged by said flanged roller, obliquely disposed rollers journalled longitudinally at the inner sides of said brackets to be engaged with the opposite edges of the rim of a car wheel, a prime mover mounted on said frame and operatively connected with said shaft and the last named of said rollers, and a handle bar extending rearwardly from said frame for maintaining the balance of the device on said rail.

2. The invention as defined in claim 1, with a second shaft journalled transversely on the top side of said frame forwardly of the prime mover, intermeshing gears between said prime mover and one end of said second shaft, chain and sprocket connections between the opposite end of said second shaft and the projecting end of the first shaft, and intermeshing bevel gears between the intermediate portion of said second shaft and said obliquely disposed rollers.

PAUL W. SCHILLING.
